United States Patent Office.

JOSEPH W. WATTLES, OF CANTON, MASSACHUSETTS.

Letters Patent No. 83,426, dated October 27, 1868.

IMPROVEMENT IN RING FOR SPINNING-MACHINE.

The Schedule referred to in these Letters Patent and making part of the same.

To all persons to whom these presents may come:

Be it known that I, JOSEPH W. WATTLES, of Canton, of the county of Norfolk, and State of Massachusetts, have invented a new and useful Improvement in Rings for Ring and Traveller Spinning-Frames; and do hereby declare the same to be fully described in the following specification; and represented in the accompanying drawings, of which—

Figure 1 is a top view, and

Figure 2, a transverse section of a spinning-frame ring provided with my invention, in the carrying out of which, I construct the ring with a trough or channel to extend around it, on its inner side, and to hold oil, for the purpose of lubricating the traveller and that or those surfaces against which it may be borne while it may be revolving on the ring-flange.

The ordinary process of oiling a traveller has been to put the lubricating-material on the top of the ring, such having to be done once in every three or four hours, or thereabouts, the period being governed by the size of the yarn, the speed of the frame, and by other circumstances, the frame being generally stopped or not in operation at the time. As heretofore made, the ring will not retain such oil, it being liable to flow down upon and from it.

With my invention, however, the traveller becomes "self-oiling," for in a stoppage of the frame so as to sufficiently lessen the draught of the yarn on the traveller, the latter will drop down and enter or extend into the oil in the trough, so that when the traveller may next be put in operation, it will be caused to lubricate the flange of the ring.

In the drawings, A denotes the ring, a the flange or part on which the traveller runs, and b is the oil-trough, the latter being shown as arranged next to the inner side of the ring.

There may be such a trough on each side of the

ring, and, if desirable, the two grooves or troughs may be connected by one or more holes or passages, so as to allow the oil to flow from one groove into the other, and stand at one level in the two.

I mention these changes as so many modes in which I have contemplated the application of my invention.

I have found that collections of fibrous waste in the oiling-trough or troughs, or in the traveller, are beneficial, as they frequently serve to transmit the oil to the traveller while it may be in operation.

I do not claim a ring as grooved in the manner as represented in the United States patent No. 66,104, and to operate with a bar projecting across the ring, the said bar being at its opposite ends inserted in such groove, which, in order to keep the bar in connection with it, has to be capped by a ring; nor do I herein intend to claim anything as shown and described in Letters Patent No. 24,681, granted to me.

In neither of the devices shown in the said patents is there an oiling-groove arranged on the inner side of the ring, and below its traveller-supporter or flange, so as to cause, on a stoppage of the traveller, its lower part to fall into the trough or groove, as is the case with my improvement.

I, therefore, claim my improved ring, as made with the traveller-supporter or rail a, and the oiling-trough b, arranged as represented in the accompanying drawings, and as hereinbefore described, such being so as to cause the traveller, on ceasing to revolve on the supporter, to dip its lower part into such groove, as and for the purpose specified, when such groove may be supplied with a lubricating-fluid.

JOSEPH W. WATTLES.
